UNITED STATES PATENT OFFICE.

BLANCHE WILLIS HOWARD, OF BANGOR, MAINE.

BATHING-SHOE.

SPECIFICATION forming part of Letters Patent No. 393,563, dated November 27, 1888.

Application filed March 6, 1888. Serial No. 266,311. (No model.)

To all whom it may concern:

Be it known that I, BLANCHE WILLIS HOWARD, of Bangor, county of Penobscot, State of Maine, have invented an Improvement in 5 Bathing-Shoes, of which the following description, in connection with the accompanying drawings, is a specification, like letters on the drawings representing like parts.

The object of my invention is to produce a 10 bathing-shoe that will be more comfortable and durable than the bathing-shoes now in use, and will also be of more attractive appearance.

Bathing-shoes have commonly been made 15 with soles of hemp or partly of cloth, as leather is unsuitable for this purpose, owing to the effect of the water upon it. The materials heretofore used have either been thick and clumsy or have been so soft and flexible as to 20 afford insufficient protection to the foot. I have discovered that a durable and efficient sole can be made of thin sheets of celluloid molded to the proper shape, preferably using two sheets for each sole, between which sheets 25 the edges of the upper are drawn, the said inner and outer sole being fastened together through the edges of the upper by rivets or other suitable fastenings. The shoe is also 30 preferably provided with a lining-sole, which may be made from a thin sheet of cork, and the entire sole is provided with several perforations to permit the water to flow freely 35 out, although the material itself is impervious, and therefore does not become water-soaked and heavy, as is the case with the materials 40 heretofore commonly used in bathing-shoes.

Figure 1 is a side elevation of a bathing-shoe embodying this invention; Fig. 2, a longitudinal section of the sole portion thereof; 45 and Fig. 3 a transverse section on line $x-x$, Fig. 2.

The upper a of the shoe may be of any suitable or usual shape and material, stout linen cloth being well adapted for this purpose.

The edges of the said upper are drawn in between the outsole b and an insole, b' , which soles are fastened together, and to the edges of the upper by rivets c , or other suitable fastenings. The said in and out soles b b' are composed of a material impervious to water and 50 of considerable rigidity, although sufficiently flexible for comfort, celluloid being the best known material to me for this purpose.

The shoe is preferably provided with a lining sole, d , which may be of cork, and the entire sole is provided with a sufficient number 55 of perforations, e , to permit the water to pass freely through it.

A sole of the kind described while being sufficiently elastic or flexible for the comfort 60 of the wearer is not soft and yielding, and thus affords a sufficient protection to the foot in walking over pebbles; and, owing to its imperviousness, it does not become soft when in 65 the water, and then harden when dry, and it does not become waterlogged or heavy when in use, so as to interfere with swimming.

I claim—

1. The combination of the upper with an outsole and an insole, each composed of a 70 sheet of celluloid molded to shape, the edges of the upper being inserted between the edges of said soles, and the latter being connected together by fastenings inserted through the edges and through the edge of the interposed 75 upper, substantially as described.

2. The combination, with the upper, of a sole composed of celluloid provided with perforations, substantially as and for the purpose 80 described.

In testimony whereof I have signed my name to this specification in the presence of two subscribing witnesses.

BLANCHE WILLIS HOWARD.
